UNITED STATES PATENT OFFICE.

SAMUEL WICKS, OF CLEVELAND, OHIO.

APPARATUS FOR RECUTTING FILES BY ELECTROLYSIS.

SPECIFICATION forming part of Letters Patent No. 637,813, dated November 21, 1899.

Application filed July 10, 1899. Serial No. 723,329. (No model.)

To all whom it may concern:

Be it known that I, SAMUEL WICKS, a citizen of the United States, residing at Cleveland, in the county of Cuyahoga and State of Ohio, have invented certain new and useful Improvements in Means for Recutting Files; and I do declare that the following is a full, clear, and exact description of the invention, which will enable others skilled in the art to which it appertains to make and use the same.

My invention relates to an improvement in means for recutting files by electrolytic action, all substantially as shown and described, and particularly pointed out in the claims.

15 In the accompanying drawings, Figure 1 is a vertical sectional elevation of my improved apparatus, showing a series of files in the bath and presumably subjected to a current. Fig. 2 is a perspective elevation of an end 20 section of the apparatus, showing certain details thereof, as hereinafter fully described.

25 A represents a suitable tank which is provided with acid-proof lining *a* of lead or the like, and is adapted to receive the acid solution or electrolyte. It may be of any preferred size and adapted to any size of files.

In the operation the files *B* which are to be resharpened become the anodes by connecting with the positive pole of an electric battery or other source of electricity—say such as shown in diagram in the drawings—and the rods *C* of carbon or the like, which are shown here as partially pocketed in the wall of the tank, become the cathodes by connecting them with the negative pole of the source of the current.

The electrolyte within the tank normally has a feeble and slow action upon iron and steel, except when under the influence of an 40 electric current, when it then becomes more rapid and caustic. The particular elements of this electrolyte may vary according to circumstances, and they may be composed of either acids or alkalies.

45 The preferred electrolyte is sulfuric acid, which may be more or less diluted with water.

As many of the rods or cathodes *C* as may be desired can be used, and there may be as 50 many as there are files, more or fewer, and all are pocketed in the wall of the tank after

the manner shown especially in Fig. 2, and a perforated lead shield *c* incloses them. The resistance and the consequent chemical action to cut all the files uniformly is more or less governed by the number of rods used, the pocketing of the same also contributing to this end. 55

The shields *c* provide protection for the files and prevent any possibility of the files 60 and rods *C* from coming into contact through accident, overcrowding, or otherwise.

The cathodes *C* are all suspended from a metallic or other suitable conducting-frame *D*, which in this case consists of rods supported by posts *d* or their equivalent on the tank and having the elements *C* suspended therefrom in electrical connection. The wire 2 from the generator *E* passes to this frame, while the opposite wire 3 goes to the several 70 anodes or files *B*. The said elements or files *B* are shown here as suspended by a spring-pressed clamp *4* from an insulating rod or bar 5, which is secured at its ends to the frame *F*, erected upon the tank and adapted to carry 75 the switch mechanism for the files, a separate switch *G* being used for each file and supported upon the horizontal bar *f* of the frame *F*. The switch *G* consists of two contact members *g* and *g'*, fixed, respectively, to the bar 80 *F* and to the metallic strip *f'*, which runs along on the top of said bar and to which the wire 3 from the generator is attached. The upper member of the switch *G*, therefore, is clamped on the said strip *f'*, while the lower 85 member is attached to the wooden or other like non-conducting-bar *f*, and a switch proper, 6, having a finger extension to control it, is rotatably secured to the lower member in this case and adapted to contact with the upper 90 member when turned on to establish the current through the file. Connection is made by a wire 7 between the switch and the clamp 4, which suspends the file, so that through these several parts a complete circuit is established and connection upon the file in the 95 solution is effected.

Each file has its own switch, and the support 5 for the files is provided with a clamp 8 at its ends, adapting it to be adjustably attached to the bar *f*, so that it can be raised or lowered, according to the length of the file to 100

be treated. The clamps 4 are provided with hooks to engage the rods 5 and are easily detached when necessary.

What I claim is—

- 5 1. In an apparatus for recutting files electrically, means to support the files singly and separately, means to adjust said files to any depth desired in the electrolyte, cathode members supported and suspended within pockets in the walls of said apparatus, and electrical connections for said files and cathode members, substantially as described.
- 10 2. An electrolyte-tank having pockets in its walls, perforated shields about said pockets, cathode members supported and suspended within said pockets, adjustable means to support and suspend files in line within said tank, and electrical connections for said cathode members and files, substantially as described.
- 15 3. An electrolyte-receptacle for recutting files electrically having pockets in its walls and shields open to the electrolyte about said pockets, cathode members suspended within said pockets and electrically connected to the negative pole of a source of electricity, in combination with a supporting-frame for the files vertically adjustable, and electrical connec-

tions for the files leading from the negative pole of the source of electricity, substantially as described.

4. In an apparatus for recutting files electrically, an adjustable non-conducting support for the files, whereby they may be raised or lowered in the bath according to size, a clamp for each file on said support, a separate switch for each file and an extensible connection therefrom to the said clamp, substantially as described.

5. The liquid-receptacle and the electrodes in the wall thereof, in combination with a frame across the receptacle and a conducting-strip along the top thereof, an adjustable file-support on said frame, a two-part switch having one part fixed to said frame and the other part engaged on said conducting-strip, and an extensible electrical connection from the switch to the file-support, substantially as described.

Witness my hand to the foregoing specification this 24th day of June, 1899.

SAMUEL WICKS.
